ATTY

UNITED STATES PATENT OFFICE.

EUGENE D. CHELLIS, OF PORTLAND, MAINE, ASSIGNOR TO NATIONAL METAL SEAL COMPANY, OF PORTLAND, MAINE, A CORPORATION OF MAINE.

CONTAINING VESSEL.

1,006,720.

Specification of Letters Patent. Patented Oct. 24, 1911.

Application filed January 2, 1908. Serial No. 408,940.

To all whom it may concern:

Be it known that I, EUGENE D. CHELLIS, a citizen of the United States, residing at Portland, county of Cumberland, State of Maine, have invented certain new and useful Improvements in Containing Vessels, of which the following is a specification.

This invention relates to containing vessels and particularly to the construction of 10 a shoulder on such a vessel.

In the formation of a mouth about a can or bottle it is frequently desired to have the same finished with an exterior shoulder. This is particularly true where there is to 15 be applied to the can or bottle mouth a closure which is to engage the bottle mouth externally and be held in place by such engagement. To provide a suitable bearing surface for the engaging parts of such a 20 closure it is necessary that this shoulder have a smooth under surface and, furthermore, that it present a firm unyielding rim over which the closure bears.

To this end I have devised my present invention which consists in the formation of 25 a shoulder reinforced and closed on its lower side to secure the results above specified.

The invention will be more fully described in the specification which follows and an 30 embodiment of the same is shown in the accompanying drawing which forms a part of said specification.

Throughout both specification and drawing like reference numerals represent corresponding parts and in the drawings:—Figure 35 1 shows, in section, a side view of a bottle neck embodying my invention, Fig. 2, a side elevation of such a neck, Fig. 3, a plan view of the same, Fig. 4 is a view of 40 the neck with the supporting disk removed, Fig. 5 is a side elevation of the removed disk, and Fig. 6, showing a shoulder engaging closure in place on such a neck.

Various modifications may obviously be 45 made in the construction, arrangement, and the interengagement of the parts without departing from the spirit of my invention.

1 indicates the mouth portion of any containing vessel. This may obviously be of 50 any shape or material but the form shown being that of a metal can having a reduced neck portion which alone appears in the drawing.

2 is a laterally flaring rim about the mouth of the neck 1 which terminates in a depending flange 3.

4 is an annular disk surrounded by an upturned rim 5 and having a central opening 6 of suitable size to fit snugly over the neck 1.

In assembling the parts the neck 1 may 60 either be formed separately, with its flange 2 and rim 3 already shaped and with the disk 4 already previously shaped and assembled thereon after which the neck 1 may be secured to the containing vessel, or, the 65 disk 4 may be formed and slipped over the neck while still in a tubular form after which the rim and flange 2 and 3 may be formed on the neck 1 and the parts brought into engagement, as shown in Fig. 1, afterward. The flanges 3 and 5 preferably have 70 a driving fit so that when the disk 4 is driven up against the under side of the shoulder it will be snugly held in place although the parts may be held by soldering or by crimping 75 the outer flange 3 upon the disk in such a way as to hold it firmly within itself. In this manner a firm, even shoulder with a smooth under surface will be formed about the mouth of the vessel so that a closure 7, 80 as shown in Fig. 6, will find suitable engagement for its spring shoulder engaging fingers 15 and its locking lip 14. The disk 4 affords an internal brace for the flange 2 and depending rim 3 and secures these parts 85 against distortion during the capping process or against damage or disfigurement during use.

What I therefore claim and desire to secure by Letters Patent is:—

In combination, a containing vessel neck having a rim about its mouth, a depending flange about said rim, a disk having an opening therein and surrounding said neck, said disk having an upwardly extending marginal flange adapted to fit within the flange on the rim and a closure on said vessel mouth having spring fingers in engagement with said disk.

In testimony whereof, I affix my signature 100 in presence of two witnesses.

EUGENE D. CHELLIS.
